UNITED STATES PATENT OFFICE.

RALPH K. MASON, OF BANTAM, CONNECTICUT, ASSIGNOR OF ONE-HALF TO JOHN H. LANCASTER, OF LITCHFIELD, CONNECTICUT.

QUICK-BREAK SWITCH.

1,420,381.

Specification of Letters Patent. Patented June 20, 1922.

Application filed June 2, 1920. Serial No. 386,125.

To all whom it may concern:

Be it known that I, RALPH K. MASON, a citizen of the United States, residing at Bantam, in the county of Litchfield and State 5 of Connecticut, have invented certain new and useful Improvements in Quick-Break Switches; and I do declare the following to be a full, clear, and exact description of the invention, such as will enable others skilled 10 in the art to which it appertains to make and use the same.

My invention relates to improvements in switches of numerous types and more particularly to those of quick break nature in which a spring is employed 15 for quickly opening the switch. Spring-opened switches with means for holding the same closed, have heretofore been used, but my invention aims to improve 20 on them by providing a single handle for closing the switch when moved in one direction and for releasing the switch-holding latch by opposite movement, to allow the switch-opening spring to act. The ar- 25 rangement is such as to prevent any possibility of slowly opening the switch, this being accomplished by permitting the handle to move idly a considerable distance toward switch-open position before tripping the 30 latch which holds the switch closed. It is thus insured that the handle will be sub-stantially in switch-open position before the moving switch means are again operatively engaged with said handle, and thus it is an 35 impossibility to impede the opening of the switch by slowly moving the handle to switch-open position. By my arrangement it is further insured that the switch cannot be left only partly closed since when the 40 operator's hand releases the handle the switch will assume and remain in either an entirely "on" or "off" position.

A further object is to provide a switch of enclosed and truly safety nature, in which 45 a door for giving access to internal parts, is locked by moving the handle to switch-closed position and released by the spring means which opens the switch.

Yet another object is to provide improve- 50 ments of the above defined nature which

may be applied equally well to switches of numerous types such as line switches, motor-starting switches, etc., whether of single or double break nature or of enclosed or open type.

With the foregoing and minor objects in view, the invention resides in the novel combination, arrangement and construction of parts hereinafter described and claimed, the descriptive matter being supplemented by 55 the accompanying drawings which form a part of this application.

Figure 1 is a front elevation of an enclosed safety switch constructed in accordance with my invention.

Fig. 2 is a side elevation showing the position of the operating handle when the switch is closed.

Fig. 3 is a view similar to Fig. 2 but showing the handle in switch-releasing position, permitting opening of the re-fusing door.

Fig. 4 is a vertical section cut substantially on the plane of line 4-4 of Fig. 1, 70 showing the switch closed.

Fig. 5 is a vertical section on the plane indicated by line 5-5 of Fig. 4.

Fig. 6 is a sectional view as indicated by line 6-6 of Fig. 5, showing the switch open.

Fig. 7 is a horizontal sectional view on 80 the plane designed by line 7-7 of Fig. 5.

Fig. 8 is a disassembled perspective view of several of the switch operating parts and the adjacent casing structure.

Fig. 9 is a side elevation partly in section, illustrating my improvements applied to an enclosed knife switch.

Fig. 10 is a sectional view on line 10-10 of Fig. 9 with parts in elevation.

Fig. 11 is a view cut approximately on 90 line 11-11 of Fig. 10, showing the switch open.

Fig. 12 is substantially a duplicate of Fig. 9, but showing the switch in open position to illustrate more clearly the relation 95 of switch operating parts then existing.

Fig. 13 is a horizontal section on approxi- mately the line 13-13 of Fig. 10.

Figs. 14, 15 and 16 are side elevations partly in section showing the application 100

of my improvements to an enclosed motor-starting switch, said views illustrating respectively the relations of parts when the switch is entirely opened, in motor-starting position, and in running position.

Fig. 17 is a vertical section taken substantially on the line 17—17 of Fig. 14.

In carrying out all forms of my invention, I employ spring-opened switch means, 10 a handle movable to one position for closing the switch against the tension of its opening means, and a latch for holding the switch closed, said latch being releasable by idle movement of the handle toward 15 switch-open position. This idle movement of the handle may be allowed by any preferred means such as those hereinafter described; the switch-opening spring and the latch may be of any adequate design and 20 may act on practically any parts having movement when the switch operates, and the means for releasing the latch from the handle may vary as occasion may dictate. I prefer however, that the latch shall be 25 provided with a releasing portion extending into close proximity with the handle and that the latter be provided with a part adapted to strike and release said latch at the proper time. This arrangement in 30 actual practice has proven to be of great advantage but other relations of parts might well be used if found desirable.

In the following, I have described the application of my improvements to several 35 forms of switches and I have entered specifically into certain details of construction which may be used. I wish to again state however, that these details need not necessarily be followed and that the improved 40 features may be adapted to switches of types other than those shown.

Figs. 1 to 8 illustrate an enclosed, double break, safety switch constructed in accordance with my invention, all switch parts 45 being housed within a cabinet 1 having a door 2 and a false front 3 provided with an opening 4. Fixed and movable bases 5 and 6 respectively are mounted in the cabinet 1 behind the false front 3, said fixed base carrying spaced contacts 7 while the movable base is provided with other contacts 8 connected by fusible means 9. One end of the movable base 6 is mounted on pivoted links 10 while its other end is connected to crank 55 arms 11 on a rock-shaft 12 having an appropriate operating handle 13.

One of the links 10 is provided with a flat lug 14 operating in a key-hole slot 15 in a link 16 which is pivoted to the door 2. 60 When the switch is closed, the lug 14 is received transversely in the enlarged end of slot 15 and thus said door is locked as seen in Fig. 4, but when the switch is opened by the spring means yet to be described, said lug is positioned for reception in the

narrow elongated part of the slot so that the door may be opened. (See Figs. 3 and 6.)

The parts so far briefly described form no part of the present invention except in 70 their association with the improvements described below and are merely disclosed to illustrate the application of such improvements to a safety switch. In this instance, the switch is of double break nature and the 75 movable base 6 forms a barrier to live parts when the switch is opened, as seen in Fig. 6, thus preventing any possibility of injury while re-fusing.

The type of switch above described is 80 disclosed in my pending U. S. application, Serial No. 309,280, filed July 8th, 1919. The casing of the switch is preferably of two sections detachably connected by the means and for the purposes revealed in my U. S. 85 application Serial No. 386,126, filed June 2, 1920.

As above indicated, I employ spring means held under tension while the switch is closed for quickly opening said switch when its 90 holding latch is released, and although such spring means may vary both in construction and location, I have shown a coiled torsional spring 17 mounted on the rock-shaft 12 with one end 18 acting against the casing 1 and 95 its other end 19 coacting with one of the arms 11 in such manner as to rapidly open the switch when the tension of the spring is released.

The form of the latch and its location 100 may vary in numerous ways but for illustrative purposes I have shown a substantially straight spring arm 20 having one end secured to the casing at 21 while its other end 22 extends through a slot in said 105 casing to a point adjacent the inner end of the handle 13. Spring 20 coacts with a stop shoulder 23 which moves on an arcuate path when the shaft 12 rotates, and although the shoulder may be carried by any suitable 110 part, I have shown the same formed on the inner end of one of the arms 11 and on a disc 24 carried by the shaft. The end 22 of the latch 20 projects beyond the shoulder 23 and I have shown a cam 13^a on the inner 115 end of handle 13, adapted to strike said latch and release it from said shoulder, when the handle has been moved a considerable distance toward switch-open position.

A positive connection between handle 13 120 and shaft 12 when closing the switch, and idle return movement of said handle toward switch-open position, may be permitted by any adequate means for allowing the necessary lost motion. In the present disclosure 125 however, I have shown the handle provided with a pin 25 which extends inwardly through a slot 26 in the casing and is operable between spaced shoulders 27 on the disc 24. This disc may be connected with the 130

shaft in any suitable manner but I prefer that said disc be provided with a rectangular opening 29 to non-rotatably receive one end of the shaft 12. A short shaft extension 5 12^a is secured to shaft 12 by a screw or the like 12^b and prevents outward shifting of the disc 24 and the adjacent arm 11, and the handle 13 is provided with a hub 13^b rotatable on said shaft extension, being held 10 thereon by a suitable washer 30 on the screw 12^b.

The operation of the switch so far described is as follows. To close the switch, handle 13 is moved rearwardly, thus causing 15 the pin 25 to thrust against one of the shoulders 27, turning the disc 24 and the rock-shaft 12 so that the crank arms 11 move the base 6 to the position of Fig. 4, in which position the contacts 8 are engaged with the 20 contacts 7 to which the line and load wires are connected. As the switch is thus closed, spring 17 is placed under tension, and when the complete closed position is reached, latch 20 engages the shoulder 23 and holds the 25 switch closed as shown clearly in Figs. 1, 2 and 7. The spring 17 will open the switch if the handle is released before latch 17 comes into play and thus there is no possibility of leaving the switch with the contacts 30 only partly engaged.

To open the switch, the handle is pulled forwardly, and during this movement, the pin 25 moves idly away from the stop 27 previously engaged thereby, the handle in 35 the meantime turning freely with respect to the shaft 12. When the handle has moved a considerable distance toward switch-open position, its cam 13^a strikes the end 22 of latch 20 and releases such latch from the 40 shoulder 23, whereupon spring 17 immediately comes into play to rapidly open the switch. There is no possible manner in which the switch may be slowly opened and thus caused to arc, since the opening movement is in no way under the control of the 45 operator after such movement starts. The spring 17 rapidly loses its tension as it opens the switch and thus the moving switch parts are not caused to strike the casing an excessive blow, as in the case with springs of 50 other types which might be used.

It will be observed that manual closing of the switch turns the door locking lug 14 to locking position and thus prevents opening 55 of the door 2 while the fuse 9 and associated parts are in circuit. The latch 20 acts to hold the switch parts and consequently this door locking means is in effective position as long as the switch is closed, 60 but when said latch is released and the spring 17 acts, said spring releases the locking means of the door in addition to opening the switch.

Figs. 9 to 12 disclose the application of 65 my improvement to an ordinary enclosed

knife switch and the essential features are approximately the same as above described. In these views, numeral 35 designates spaced contacts and 36 refers to pivoted switch blades connected by a link 37 with 70 a crank 38 on a rock-shaft 39 similar to the rock-shaft 12. This shaft is provided with a handle 40 having lost motion thereon, a spring 41 is shown acting on the shaft to open the switch, and a resilient latch 75 arm 42 is provided to hold the shaft in switch-closed position. Shaft 38 may also carry a cross-head 43 connected with a slotted link 44 to lock the door 45 of the enclosing casing 46.

The lost motion connection between the handle 40 and the shaft 39 differs slightly from that above described, as does also the latch mechanism. I have shown a plate 47 secured on shaft 39 and shouldered at 48 85 to coat with a pin 49 on the handle 40 to close the switch, and the plate 47 is equipped with a shoulder 50 coacting with a resilient latch-arm 42. This arm is shown approximately U-shape, with one end secured to the 90 casing while its other end extends to a point at which it may be engaged by a releasing cam 51 formed on the inner end of the handle 40.

To close this form of switch, the handle 95 is moved rearwardly to the position seen in Fig. 9, the shoulder 48 and pin 49 then coacting in the manner indicated in Fig. 11, to establish a positive connection between said handle and the shaft 38, with the result that the switch blades 36 are closed. While this closing is taking place, the spring 100 41 is being placed under tension and the head 42 is being moved to operative position, and when complete closing of the 105 switch has occurred, the shoulder 50 engages the latch 42 and thus all parts are held in switch-closed position.

As in the construction above described, slow opening of the switch cannot be effected, but idle movement of the handle 40 toward switch-open position, causes the cam 51 to strike and release the latch 42, thereby allowing spring 41 to act, opening the 110 switch and releasing the locking means of 115 the door 45.

In Figs. 14 and 17 I have illustrated an enclosed motor-starting switch embodying my improvements. The construction of this switch is almost identical with that shown 120 in Figs. 1 to 8. The movable base 55 however, which is actuated by a rock-shaft 56, carries a non-fusible switch means 57 and fusible switch means 58 for successive engagement with contacts 59 on a fixed base. 125 The handle 60 is mounted on the rock-shaft 56 and connected therewith in the same manner as described in Figs. 9 to 12, but this handle is provided with a movable stop 61 cooperable with a fixed stop 62 on the cas- 130

ing to arrest movement of the handle when the switch has been set in starting position, that is with the non-fusible switch bar 57 engaged with the contacts 59 as in Fig. 5 15. When the stop 61 is released after proper starting of the motor, the handle 60 may be moved further to the rear to disengage the bar 57 from the contacts 59 and engage the fusible means 58 therewith, thus 10 setting the switch in running position as seen in Fig. 16.

A suitable spring 63 acts on an appropriate switch moving part for opening the switch and a latch 64 is employed to hold 15 the switch closed against the tension of said spring, said latch being here shown as acting on a shoulder 65 carried by a plate 66 which is suitably mounted for movement with the shaft 56. Latch 64 is positioned 20 to be struck by a cam 67 on the handle 60 so that said latch is released by idle movement of the handle toward switch-opened position. This idle movement of the handle preferably takes place until after the movable stop 61 has passed the fixed stop 62, but not necessarily so, since these stops are so shaped as to cause the one to ride freely over the other during movement of the handle toward the position at which it opens 25 30 the switch. As soon as the handle releases the latch 64, the spring 63 acts to open the switch and also to release the locking means of the cabinet door, if such locking means be employed.

35 In all forms, my invention is simple and comparatively inexpensive, yet it is highly efficient, reliable and in every way desirable. In all types of construction, movement of the handle in one direction, positively closes 40 the switch and locks the same closed against the tension of suitable spring means. Movement of the handle in the other direction to a considerable extent, releases the switch-holding means and thus causes the spring 45 means to quickly open the switch without arcing. In no instance, is it possible for the operator to slowly open the switch and thus endanger the interengaging parts thereof by subjecting them to arcs, since after 50 the switch parts start on their opening movement, they are in no way under the control of the operator and must continue quickly to the end of their opening movement.

Excellent results may be obtained from 55 the several details shown and described, but within the scope of the invention as claimed, numerous other arrangements and constructions may be employed. Furthermore, the specific details shown in connection with 60 the several forms of switches, are not usable only with their respective forms, but with others if found desirable.

I claim:

1. An enclosed switch comprising a casing, 65 a spring-opened switch member therein,

a handle pivoted on the exterior of the casing and connected with said switch member for closing the switch against the action of its opening spring, and a latch in said casing for holding the switch in closed position, 70 said latch having a tripping portion extending to the exterior of the casing adjacent the pivoted end of the handle, said handle having idle movement toward switch-off position when the switch is closed and being 75 adapted when so moved to strike said tripping portion of the latch to release the latter and permit the switch to open under the action of its opening spring.

2. An enclosed switch comprising a casing, 80 a movable switch member in said casing, a rock-shaft extending across said casing and connected with said switch member, a spring exerting a stress on said shaft to turn the same to switch-off position, a pivoted handle on the exterior of the casing axially connected with said rock-shaft and having lost motion with respect thereto, a latch mounted in the casing and having a tripping portion extending to the exterior thereof adjacent the 90 inner end of the handle, said rock-shaft having means cooperable with said latch to hold the switch in on position, said handle having a cam adapted upon idle movement of the handle toward switch-off position, to strike 95 said tripping portion of the latch and release the latter.

3. An enclosed switch comprising a casing, 100 a movable switch member in said casing, a rock-shaft extending across said casing and connected with said switch member, a spring exerting a stress on said shaft to turn the same to switch-off position, a handle on the exterior of the casing loosely mounted on said rock-shaft, a lost motion connection between said handle and shaft, a plate secured 105 on said shaft within the casing, said plate having a shoulder, and a latch arm mounted in said casing and co-operative with said shoulder to hold the rock-shaft in switch on 110 position, said latch arm extending at one end to the exterior of the casing adjacent the inner end of the handle, said handle having a cam adapted upon idle movement of said handle toward switch-off position, to strike 115 said extended end of said latch arm and release the latter.

4. A switch comprising switch means, a rock-shaft connected with said switch means, 120 a handle loose upon said shaft, a plate secured on said shaft in a plane transverse thereto and having a shoulder, a projection on said handle cooperable with said shoulder to close the switch, spring means for opening the switch, and a latch for holding said 125 switch in closed position.

5. A switch comprising switch means, a rock-shaft connected with said switch means, 130 a handle loose upon said shaft, a plate secured on said shaft in a plane transverse

- thereto, said plate having a pair of shoulders spaced apart on an arcuate line concentric with the shaft, a projection on the handle cooperable with said shoulders, and spring 5 means for effecting switch moving turning of said shaft independently of said handle.
6. In a switch, movable switch parts and a rock-shaft connected operatively therewith, a spring for moving the switch parts to open 10 position, a disc non-rotatably mounted on one end of said rock shaft and a latch coacting with said disc to hold the switch closed, a shaft extension secured to said shaft end and preventing removal of said disc, a handle 15 mounted on said shaft extension and having means for releasing said latch, and means for operatively connecting said handle and disc and for allowing lost motion between them.
- 20 7. A switch comprising a cabinet having a door, switch means in said cabinet, a lock for said door, switch actuating means hav-
- ing a single handle for closing said switch means and moving said lock to active position, an independent latch coacting with said 25 actuating means for holding the switch means closed and the lock applied, and spring means for opening the switch and releasing the lock when said latch is released.
8. A switch comprising a cabinet having 30 a door, locking means for said door, switch means in the cabinet, a single rock-shaft for operating the door lock and the switch means, spring means acting on said rock-shaft for releasing the lock and opening the 35 switch, a latch for holding said shaft in switch-closed position, and a handle for moving said shaft to switch-closed position and for releasing said latch when moved toward switch-open position. 40

In testimony whereof I have hereunto set my hand.

RALPH K. MASON.
